(57) **CLAIM**

We claim the ornamental design for a shackle, as shown and described.

DESCRIPTION

FIG. 1 is a perspective view of a shackle showing our new design;

FIG. 2 is a front view of FIG. 1;

FIG. 3 is a rear view of FIG. 1;

FIG. 4 is a cross-sectional view of FIG. 1 taken along the lines 4—4 of FIG. 2;

FIG. 5 is a right side view of FIG. 1, wherein the left side view is a mirror image;

FIG. 6 is a top view of FIG. 1;

FIG. 7 is a bottom view of FIG. 1;

FIG. 8 is a perspective view of FIG. 1 shown in an alternate environment;

FIG. 9 is a front view of FIG. 8;

FIG. 10 is a rear view of FIG. 8;

FIG. 11 is a right side view of FIG. 8, wherein the left side view is a mirror image;

FIG. 12 is a top view of FIG. 8; and,

FIG. 13 is a bottom view of FIG. 8.

The broken lines shown in the drawing disclosure are for illustrative purposes only and form no part of the claimed design.
